[57] CLAIM

The ornamental design for a wheel cover, as shown and described.

DESCRIPTION

FIG. 1 is a front elevational view of the wheel cover showing my novel design;

FIG. 2 is a side elevational view thereof;

FIG. 3 is a sectional view taken along the plane indicated by line 3—3 in FIG. 1; and

FIG. 4 is a perspective view thereof.

The broken line showing of an emblem on the center disc of the wheel cover shown in FIGS. 1 and 3 of the drawing is for illustrative purposes only and forms no part of the claimed design.
